UNITED STATES PATENT OFFICE

HYMAN FREEDMAN AND NATHAN M. FREEDMAN, OF CHICAGO, ILLINOIS, ASSIGNEES
TO DAVOPLANE BED COMPANY, OF CHICAGO, ILLINOIS, A CORPORATION OF
ILLINOIS.

FOLDING SPRING-MATTRESS

1,246,254.

Specification of Letters Patent. Patented Nov. 13, 1917.

Application filed May 25, 1914. Serial No. 340,661.

To all whom it may concern:

Be it known that we, HYMAN FREEDMAN and NATHAN M. FREEDMAN, citizens of the United States, and residents of Chicago, in 5 the county of Cook and State of Illinois, have invented a new and useful Folding Spring-Mattress, of which the following is a specification.

Our present invention has special reference to 10 spring mattresses adapted to be installed in davenport beds which must be capable of folding within the seat portion of the davenport when the same is closed to form a davenport.

15 The special objects of our present invention are the provision of a structure which will be simple and economical of manufacture; which will be simple and positive in operation, which will afford space between 20 the sections of the mattress for the stowage of the bedding in folded position; and which will be firm and rigid in open position so as to be capable of giving satisfaction in any service to which beds may be put.

25 We attain the above objects by means of the structure illustrated in the accompanying drawing, in which:

Figure 1 is an end elevation of a davenport bed with our spring mattress in open 30 position and assembled therewith, the arm of the davenport being broken away to show the end of the mattress structure;

Fig. 2 is an end elevation of the spring mattress structure the folding operation 35 having been commenced;

Fig. 3 is a view similar to Fig. 2 in which the closing operation is more advanced than is illustrated in Fig. 2;

Fig. 4 is an enlarged detail of the hinging 40 link or plate from the side opposite to that shown in Figs. 1, 2, and 3;

Fig. 5 is a top plan of the structure shown in Fig. 4; and

Fig. 6 is a plan of the spring mattress in 45 open position.

Similar reference characters refer to similar parts throughout the several views.

The mattress structure comprises two frames hinged together and stretched between 50 the members constituting the frames is a suitable spring and wire fabric. Each frame comprises a single side rail 1, between the ends of which extend end rails 2, 2. The end rails are preferably made of L section 55 angle iron, with one flange or web, 2^a, there-

of, disposed horizontally and extending upon the inside of the frame, and the other flange or web 2^b extending vertically.

A standard, 3, is secured to either end of the side of the seat structure of the davenport and to the tops of the standards, 3, by means of the pintle 3^a, are pivotally secured the inner ends of the end rails, 2, 2, of what may be regarded as the outer frame of the spring mattress, the horizontal flanges 60 or webs, 2^a, thereof being cut away at the ends to permit the standards to come upon the inner surfaces of the vertical flanges or webs, 2^b, thereof. To the outer face of each vertical flange or web, 2^b, just in front of its pivotal connection with the standard, 3, is pivotally secured a hinge plate, 4, by means of a pintle 4^a, which hinge plate is sufficiently long to extend beyond the connection between the end rail and the standard. The hinge plate 4 is sufficiently deep 65 to extend below the end rails, and to the inner end in line with its connection with the end rail of the front frame it is pivotally secured by a pintle 4^b to the end rail, 2, of 70 the inner or rear frame of the spring mattress. A stop, 5, is provided in the upper part of each hinge plate 4 to contact with the end rail of the outer frame when the outer frame has been swung to fully open 75 position, and a headed pin 6 is provided upon the inner face of the inner end of each hinge plate under the head of which the vertical web 2^b of the end rail of the inner frame extends when it has been swung into 80 upward or fully open position. This headed pin 6 besides limiting the relative movement between the hinge plate and the inner end rail co-operates with the pivotal connection between the hinge plate and the inner 85 end rail to resist the pull of the wire and spring fabric secured to the horizontal flange or web 2^a thereof.

It will now be seen, especially in connection with Figs. 1, 2 and 3, that as the outer 90 section is swung up and rearwardly around its pivotal connections with the standards, 3, the forward edge of the inner section of the mattress frame will be swung downwardly and forwardly through its pivotal 95 connection with the rear of the hinge plate 4.

To positively secure a corresponding movement of the rear of the inner section of the mattress frame and to maintain the inner portion of the inner frame rigidly horizon- 100 105 110

tal in fully open position, we provide a toggle comprising the links 7 and 8 pivoted together at one end, the other ends of which are respectively pivoted at 10 and 11 to the 5 seat structure of the davenport and the rear end of the end rail of the inner section. Running from the pivotal connection between the links, 7 and 8, to a suitable point in the hinge plate, 4, to impart the necessary 10 movement is a link 12, which will positively cause the lowering or elevation of the rear part of the rear section of the mattress frame by causing the links 7 and 8 to aline with each other or to fold or assume an angular 15 relation to one another.

For the purpose of supporting the outer edge or portion of the outer section of the mattress frame in fully open position, we 20 pivot to the forward ends of the end rails 2, legs 13 and to the legs 13, just below their pivotal connection with the end rails is pivoted a link 14 the other end of which is pivoted to the depending forward end of the hinge plate, 4, just below its point of connection with the end rail. This construction, as clearly shown in Figs. 1, 2, and 3, 25 will cause the opening of the leg when the outer section of the mattress frame is unfolded and will cause the leg to be swung or 30 folded close to the end rail when the mattress is folded.

Any spring fabric may be stretched between the rails constituting the mattress frame. We have illustrated in the drawings 35 such a fabric made of connecting wire links, 15, so as to form a square mesh which mesh is secured at suitable intervals to the mattress frame by helices 16.

Having thus described our invention what 40 we claim as new and desire to secure by Letters Patent, is:—

1. A folding spring mattress for davenport beds comprising standards adapted to be mounted upon the seat structure of a 45 davenport, a mattress frame comprising two sections each consisting of two end rails and a side rail, pivotal connections between the free ends of the end rails of one of said sections and said standards, hinge plates pivotally secured to the end rails of said last mentioned section mediate its ends, pivotal connections between the end rails of the other of said mattress sections and the opposite ends of said hinge plates.

50 2. A folding spring mattress for davenport beds comprising standards adapted to be mounted upon the seat structure of a davenport, a mattress frame comprising two sections each consisting of two fabric carrying end rails and a side rail, pivotal connections between the free ends of the end rails of one of said sections and said standards, hinge plates pivotally secured to the end rails of said last mentioned section mediate 55 its ends, pivotal connections between the

end rails of the other of said mattress sections and the opposite ends of said hinge plates, and means for resisting the pull of the fabric carried by said hinge plate adapted to be engaged by the forward ends of the frame forming said other section when said mattress frame is in fully open position. 70

3. A folding spring mattress for davenport beds comprising standards adapted to be mounted upon the seat structure of a davenport, a mattress frame comprising two sections each consisting of two fabric carrying end rails and a side rail, the terminals of the end rails of one section being rounded; pivotal connections between the free ends of the 75 end rails of one of said sections and said standards, hinge plates pivotally secured to the end rails of said last mentioned section mediate its ends, pivotal connections between the end rails of the other of said mattress sections and the opposite ends of said hinge plates, and headed pins carried by said hinge plate the head of which engages over the rounded forward ends of the frame forming said other section. 80

4. In a folding bed bottom, an inner bed bottom section, an outer bed bottom section, a link pivoted to one of said sections and also pivoted to the other of said sections, the axes of the link pivots being spaced apart, a 85 support on which said outer section is pivotally supported at its side adjacent said inner section, a toggle comprising pivotally connected limbs, one of which has a supporting pivot in fixed relation to said support and the other limb being pivotally and supportingly connected to said inner section remote from said outer section, and a link 90 pivotally connected at one end to the first mentioned link, the other end of said last mentioned link being connected to the medial part of said toggle, in such manner that the swinging movement of the first mentioned link moves the limbs of the toggle relatively to each other in folding and unfolding the bed bottom. 100

5. A convertible seating device comprising a rigid support member of unitary character and a foldable sectional bed bottom carried thereby adapted to hold the bedding in place 115 thereon when folded, said support member having a rigid upright member or standard on its front part and said bed bottom having a border frame including a pair of mattress supporting rails and a connecting hinge member therefor adapted to permit of folding the sections in one direction, and lifting means arranged to act between the back part of said support member and the adjacent part of the bed bottom, the upper or outer of said rails being pivoted at its hinge end to said standard, said hinge member being pivoted to said outer rail near but spaced forwardly from the stationary pivot on said standard, and the lower or inner of 120 125 130

said rails being swingingly supported near its ends by said hinge member and said lifting means respectively, said hinge member having operative connection with said lifting means for coaction in raising and lowering said inner rail, as said outer rail is swung forward and backward respectively in unfolding and folding said bed bottom.

6. A convertible seating device comprising a support and a foldable sectional bed bottom carried thereby, said support having a standard adjacent to one edge and rigid therewith, and lifting means spaced from said standard and connected at opposite ends to said support and said bed bottom respectively for raising and lowering one of the sections thereof, said bed bottom comprising an outer section turnably connected

to said standard adjacent to its inner edge, a connecting section pivoted at one edge to 20 said outer section at a point spaced from said standard, and an inner section pivoted to said connecting section and supported in part thereby, and a link having its ends operatively connected to said lifting means 25 and to said connecting section respectively for actuation of the former by the movement of the latter.

In testimony whereof we affix our signatures in the presence of two witnesses.
